FOLDABLE DRYING RACK

Edward M. Holt, Texarkana, Ark.

Application October 7, 1947, Serial No. 778,426

2 Claims. (Cl. 211—104)

1

This invention relates to foldable drying racks, and more particularly to a portable rack adapted to be supported on an object such as a door or chair when in use and stored in some convenient, out-of-the-way place when not in use.

It is among the objects of the invention to provide a foldable, portable drying rack which may be folded into a compact package requiring a minimum amount of storage space, and unfolded to provide a rack of large capacity which may be conveniently supported on a chair, door or similar object, and which, when supported on a door, does not interfere with closing of the door or use thereof, and which is of simple, durable and economical construction, and may be quickly and easily folded for storage or set up for use.

Other objects and advantages will become apparent from a consideration of the following description in conjunction with the accompanying drawings, wherein:

Figure 1 is a perspective view of a drying rack illustrative of the invention when in unfolded or operative position;

Figure 2 is a perspective view of the drying rack when folded for storage;

Figure 3 is a transverse cross-section on a somewhat enlarged scale taken substantially on the line 3—3 of Figure 1.

With continued reference to the drawings, the improved rack generally comprises an elongated bar 10, a pair of hangers 11 and a plurality of rods 12.

The bar 10 is preferably of generally rectangular cross-sectional shape, as is clearly illustrated in Figure 3, and may be formed of wood, synthetic resin plastic, metal or other suitable material. This bar is provided with a plurality of rod-receiving openings 13 which are preferably disposed at substantially equal intervals lengthwise of the bar. Each of these openings is specially shaped to conveniently receive and securely hold an end portion of a respective rod 12, the shape of the openings being best illustrated in Figure 3. From an inspection of Figure 3, it will be noted that each rod-receiving opening 13 includes a tapered well 13a of circular cross-section opening to one side of the bar and having a depth less than the corresponding thickness of the bar so that the well does not extend entirely through the bar. The well opens to a face of the bar which is in substantially vertical position when the rack is in the operative condition illustrated in Figure 1. It will be noted that the inner end of the tapered well 13a is somewhat larger than the outer end which opens to the face 10a of the

bar, and that a recess 13b is provided which extends from the top side of the well 13a to the upper face 10b of the bar when the rack is in operative position. This recess 13b opens to the face 10a of the bar, but extends from this face along the face 10b a distance materially less than the depth of the well 13a, the extent of the recess 13b being illustrated as somewhat less than one-half the depth of the well. The recess 13b has a width sufficient to receive an end portion of a rod 12 and facilitates the insertion of the rod end portion into a rod-receiving opening in the bar. In inserting a rod end portion into an opening in the bar, the end portion is first positioned in the corresponding recess 13b from the upper face 10b of the bar. It is then moved downwardly into the well 13a and forced inwardly until its end contacts the bottom of the well. The tapered shape of the well renders it easy to force the end portion of the bar into the well and firmly clamps the rod in operative position once it has been assembled with the bar in the manner illustrated in Figure 3.

Each of the hangers 11 has a channel-shaped cross-section and may be conveniently formed of thin malleable metal, such as sheet aluminum. Each hanger has one end pivotally connected to a respective end of the bar 10 by suitable means, such as the respective rivets 14, and has the outer portion of its inner flange cut away on a slant or diagonal line, as indicated at 15, to facilitate folding and unfolding the hangers between the operative position illustrated in Figure 1, in which the hangers are substantially perpendicular to the bar 10, and the rods 12, and the folded position illustrated in Figure 2 in which they lie closely along the respective end portions of bar 10 and receive the bar between the opposite flanges thereof.

Respective hooks 16 are provided at the ends of the hangers 11 opposite the ends pivotally connected to the bar 10. These hooks are flat and preferably of generally rectangular shape and may conveniently be formed by extending the corresponding end portions of the outer flanges 17 of the hangers and making two spaced-apart, right angle bends in these extended portions. These hooks extend from the sides of the hangers opposite the sides at which the rods 12 extend from the openings 13 so that when the hooks are operatively engaged with the top of a door, or with some other supporting object, the rods will extend away from the face of the door or from the object.

Hooks 16 have a depth sufficient to receive the

2

55

thickness of a conventional door and suitable pads 18 are secured in the hooks to prevent the hooks from marring the surface of an object upon which the rack is mounted. Suitable pads 19 are also provided on the hangers at the pivoted ends thereof to provide cushioned abutments at the opposite ends of the bar so that the rack may bear against the surface of a door or other supporting object without marring the surface thereof.

In order to reduce the rack from the operative position illustrated in Figure 1 to the folded condition illustrated in Figure 2, the rods 12 are first removed from the bar 10. The bar and hangers are then removed from the supporting object and the hangers folded down along the corresponding end portions of the bar. The rod and the folded bar and hanger assembly may then be placed together in an extremely small space. Preferably, the bar 10 has a length corresponding to the width of a conventional door and may conveniently carry as many as eight rods, as illustrated, the length of which may be substantially equal to the length of the bar 10, thereby providing a drying rack of large capacity when in assembled, operative condition.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed is:

1. A foldable drying rack comprising an elongated bar of rectangular cross-section having a plurality of rod-receiving openings therein disposed at substantially equal intervals lengthwise of said bar and each including a tapered well of circular cross-section opening to one face of said bar and having a depth less than the corresponding thickness of the bar, and a recess extending from one side of said well to a second face of said bar substantially perpendicular to said one face and inwardly from said one face a distance less than the depth of said well, the inner end of said well being larger than the outer

end thereof opening through said one face, a plurality of cylindrical rods each having an end portion inserted in a respective recess in said bar, said rods extending in the same direction from said bar substantially perpendicular thereto, a pair of hangers of channel-shaped cross-section each pivotally connected at one end to a respective end of said bar and movable between a position in which they overlie respective end portions 10 of said bar and a position in which they are substantially perpendicular to said bar and said rods, and a flat hook secured to the end of each hanger opposite the end thereof connected to said bar, said hooks projecting from the sides of said hangers opposite the sides at which said rods project.

2. A foldable drying rack comprising an elongated bar of rectangular cross-section having a plurality of rod receiving openings disposed at substantially equal intervals along one side thereof, a pair of hangers of channel shaped cross-section each receiving a respective end of said bar between the flanges thereof, respective pins extending through said bar near the opposite ends thereof and through said hanger flanges near corresponding ends of said hangers to pivotally connect said hangers to said bar, said hangers, when folded, lying closely along said bar and receiving said bar between the flanges thereof, a respective flat hook on each hanger near the end of the latter opposite that pivotally connected to said bar, said hooks projecting to the side of said bar opposite said openings, and a plurality of spaced apart, substantially parallel rods inserted at corresponding ends into respective openings in said bar.
